(57) **CLAIM**

The ornamental design for a tire as shown and described.

DESCRIPTION

1. Tire
2. Tire
- 1.1 : Front
- 1.2 : Enlarged partial view of FIG. 1.1
- 1.3 : Left perspective view
- 1.4 : Enlarged partial view of FIG. 1.3
- 1.5 : Left
- 1.6 : Right perspective view
- 1.7 : Enlarged partial view of FIG. 1.6
- 1.8 : Right
- 2.1 : Front
- 2.2 : Enlarged partial view of FIG. 2.1
- 2.3 : Left perspective view
- 2.4 : Enlarged partial view of FIG. 2.3
- 2.5 : Left
- 2.6 : Right perspective view
- 2.7 : Enlarged partial view of FIG. 2.6
- 2.8 : Right

The broken lines in FIG.1.1, FIG.1.3 and FIG.1.6 are demarcations of the portion of the design visible in the enlarged partial views of FIG.1.2, FIG.1.4 and FIG.1.7, and form no part of the claimed design. The broken lines in FIG.2.1, FIG.2.3 and FIG.2.6 are demarcations of the portion of the design visible in the enlarged partial views of FIG.2.2, FIG.2.4 and FIG.2.7, and form no part of the claimed design. The second embodiment is different from the first embodiment only at that the second embodiment repeats a tread pattern in the middle to widen the tire.

1 Claim, 16 Drawing Sheets
